US00D690063S

(12) **United States Design Patent**
Kent et al.

(10) **Patent No.:** US D690,063 S
(45) **Date of Patent:** ** Sep. 17, 2013

(54) **CLEANING MACHINE**

(75) Inventors: **Steven Rodger Kent**, Ash Flat, AR (US); **Willie Dee Kent**, Oro Valley, AZ (US)

(73) Assignee: **Kent Research Corporation**, Ash Flat, AR (US)

(**) Term: **14 Years**

(21) Appl. No.: **29/410,856**

(22) Filed: **Jan. 12, 2012**

(51) **LOC (9) Cl.** 15-05

(52) **U.S. Cl.**

USPC D32/20; D32/22

(58) **Field of Classification Search**

USPC ..... D32/22, 30-31, 34, 19-20; 55/429, 55/337, DIG. 3; 15/410, 347, 328, 350, 352, 15/353, 361, DIG. 8, 246.2, 320-322, 409, 15/28, 23, 179, 97.1, 24; 451/466

(57) **CLAIM**

The ornamental design for a cleaning machine, as shown and described.

DESCRIPTION

FIG. 1 is an isometric view of a cleaning machine showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an isometric view thereof in a collapsed position. The broken lines are for illustrative purposes only and form no part of the claimed design.
